VACUUM EVAPORATOR OF THE
EJECTOR PUMP TYPE
Jerome G. Daviau, 50 Main St.,
Waterville, Maine 04901
Filed June 3, 1966, Ser. No. 565,028
10 Claims. (Cl. 159—5)

This application is a continuation-in-part of my co-pending application Ser. No. 420,081 filed Dec. 21, 1964, now abandoned.

This invention relates to pumps of the type known as jet pumps. More particularly, the invention is directed to a pump or entraining device which utilizes a motive liquid to pump a fluid by entraining the fluid with the liquid. The fluid to be pumped may comprise a liquid or a gas.

Generally, certain types of jet pumps are known in the art, and a typical jet pump includes an ejector nozzle which ejects a motive liquid past an opening in a conduit or container containing the fluid to be pumped. The pumping action depends upon a sufficient vacuum or partial vacuum being produced in the proximity of the opening to draw or pump the fluid from its container. In such prior art devices a rather large ejector nozzle is required to produce a sufficient vacuum for the pumping action, and as a result large quantities of the motive liquid must be moved through the nozzle with a large consumption of energy attendant with such fluid movement.

This invention is based upon the discovery that a jet pump may be so constructed that the pumping or entraining force may be carefully controlled with a resulting exceptional efficiency of operation and with a relatively low energy requirement.

The jet pump of my invention is constructed to provide a particularly shaped flat entrainment channel in which the motive liquid progressively decreases in pressure as it moves from its entrance into the channel toward its exit from the channel. The entrainment channel is provided with one or more communication means to a chamber or reservoir containing the fluid to be pumped and the communication means are arranged to conduct volumes of fluid from the reservoir chamber into the entrainment channel. With the construction of this invention, the motive fluid undergoes such an expansion as it passes through the entrainment channel that an exceptionally large volume of fluid is entrained. This results in a smaller energy consumption and a smaller quantity of motive liquid to pump a given quantity of fluid than has been heretofore possible.

It is also contemplated that the jet pump of this invention may be utilized to reduce pressure in a chamber for the purpose of increasing the evaporation rate of a solvent from a solution. Such an application would be useful in a system such as is described in my United States Patent No. 3,206,380 issued Sept. 14, 1965. In that system, a jet pump device would be useful in improving the evaporation rate of water vapor from sea water and in removing the water vapor from a chamber containing the sea water solution. When the jet pump of this invention is utilized to reduce pressure in a chamber for the purpose of increasing an evaporation rate in the chamber, it has been found that a relatively small quantity of motive liquid produces lower pressures in larger chambers than has been possible with prior devices.

The invention will be described with reference to several embodiments, and in certain embodiments a provision is made for adjusting the operation of the device to compensate for pressure conditions within the device.

In addition to the advantages which will be obvious from the above discussion, the present invention also has

2

the advantage of simplicity, ease of construction, and ruggedness. Also, by using the construction of this invention it is possible to more closely control the operation of a given pump by making certain simple adjustments. Furthermore, the jet pump of this invention is so constructed that it may be operated in any attitude without affecting its efficiency.

For a better understanding of the present invention, reference is made to the accompanying drawings in which:

FIGURE 1 is a sectional side view of a first embodiment of the jet pump of my invention;

FIGURE 2 is a view taken along line 2—2 of FIGURE 1, showing a top sectional view of the jet pump;

FIGURE 3 is a sectional side view of a second embodiment of this invention;

FIGURE 4 is a sectional side view of a further embodiment;

FIGURE 5 is a top sectional view of the FIGURE 4 embodiment, as taken along line 5—5 of FIGURE 4; and

FIGURE 6 is a sectional side view of an outlet portion of the jet pump of this invention, showing an adjustable gate means for the outlet.

The device shown in FIGURE 1 includes an entrainment channel 10 having an inlet end 12 for the entrance of entrainment liquid, and an outlet 14 for the exhaustion of the entrainment liquid together with the fluid which is being pumped by the device. Adjacent to the entrainment channel 10 is a chamber or reservoir 16 which has an inlet 18 for receiving the fluid to be pumped. Communication means 20, 22 and 24 are provided between the chamber 16 and the entrainment channel 10 so that the fluid to be pumped may be drawn into the entrainment channel.

The entrainment channel 10 is formed by spacing one surface of a triangular-shaped base plate 26 parallel to a surface of a similar shaped triangular plate 28 so that the plates are equally spaced from one another. The space so formed is enclosed with walls 30 and 32 along two legs of the triangle as shown in FIGURE 2. The plates 26 and 28 may be made of stainless steel or any suitable material, and the remaining parts of the jet pump may be made of a similar material. With the plates 26 and 28 arranged as just described, it will be seen that a triangular-shaped channel is formed having a slit-like opening 14. The opening 14 is at the base of the triangular plates and this will be an outlet for the mixture of fluids leaving the entrainment channel 10. Located at the vertex opposed to the base of the triangular plate 26 and in substantial axial alignment with the outlet 14, is an inlet 12 which is formed by placing the pipe 34 in communication with the entrainment channel 10. The pipe 34 is provided with a slit 36 at its point of juncture with the base plate 26 so that the inlet 12 is formed. The remainder of the pipe end is welded or otherwise secured to the base plate 26 and the plate 28 so that a fluid-tight communication is formed between the pipe 34 and its junction with the entrainment channel 10. Thus, there is formed an entrainment channel 10 which has an inlet 12 for receiving a motive entraining liquid, openings for receiving the fluid to be pumped, and an outlet 14 for discharging the motive liquid and its entrained fluid.

The flat plate construction of the channel gives a particular advantage in permitting an easy variation in the capacity of the pump by varying the spacing between the plates 26 and 28. This spacing can be related to the other dimensions of the pump to give carefully controlled and predicted performances of any given jet pump construction.

The particular diverging shape of the channel 10 causes a rapid expansion of the motive liquid as it progresses from the inlet end 12 of the channel to the outlet end 14 of the channel, and as a result of this expansion the

outlet end of the channel is at a much lower pressure than the inlet end of the channel. Since the plate 28 includes one or more openings communicating with a source of fluid to be pumped, it can be seen that the low pressure developed by the large expansion area in the channel 10 causes fluid to be drawn into and entrained with the motive liquid in channel 10, and this action may be described as a jet action or a pumping action.

The communication means 20, 22 and 24 provide openings for a fluid to be drawn into the channel 10 and are shown as three in number in the FIGURE 1 embodiment, but any number may be incorporated in this device. Looking at the openings, as viewed in FIGURE 1, it can be seen that the cross-section of opening 20 is proportionally wider than the opening 22, and opening 22 is wider than opening 24. This adjustment in the cross-sectional width of the opening corresponds with the comparative liquid velocities in the channel 10 as related to a particular opening. The liquid velocity within the channel progressively decreases as it travels from the inlet 12 to the outlet 14, and correspondingly, the cross-sectional widths of the openings 20, 22 and 24 progressively decrease to accommodate the changing velocity of the motive liquid. However, it is to be noted that although the velocity of the liquid decreases in its movement toward the outlet end of the channel, its entrainment capabilities remain relatively high because of the diverging shape of the entrainment channel. Thus, the opening 24 is smaller in cross-sectional width than the opening 20 but the entrainment capabilities of the opening 24 are just as great as opening 20 because opening 24 is longer in length than the opening 20. This progressively longer length of the openings as viewed in FIGURE 2 is made possible by progressively greater width of the entrainment channel 10, and, accordingly, greater entrainment action is possible.

The openings 20, 22 and 24 may communicate in any suitable manner, with a source of fluid to be pumped, however, the preferred embodiment of this invention places the source of fluid immediately adjacent to the openings leading to the entrainment channel. This arrangement is shown in FIGURE 1 where the chamber or reservoir 16 contains fluid which is to be pumped into the entrainment channel. In this arrangement, the plate 28 provides a common wall between the fluid chamber 16 and the entrainment channel 10, so that the fluid may be drawn from the chamber 16 through the openings 20, 22 and 24. It will be seen that the openings 20, 22 and 24 are formed by cutting the appropriate size and shape through the plate 28 which is the common wall between the chamber 16 and the entrainment channel 10. The chamber 16 includes side walls which are preferably coextensive with the side walls 30 and 32, and these walls are attached to the plate 28 to provide a liquid seal between the chamber 16 and the entrainment channel 10 at the point of junction between the walls and the plate 28. In addition, an end wall 38 is provided at the base of the triangular-shaped chamber 16 between the walls 30 and 32, and this end wall is likewise sealed in its attachment to the plate 28. A top wall 40 is provided at a suitable height above the plate 28. The top wall 40 may be sealed around its perimeter to the top edges of the walls 30, 32 and 38 with the exception of a portion which is left open for communication with an inlet 18 to the chamber 16. The inlet 18 may enter the chamber at any suitable point and communicates with the source of fluid to be pumped, such as to a reservoir container, or other source of supply.

It may be desired to use the jet pump just described for creating sufficiently low pressures in a chamber to cause an evaporation of a liquid from a solution and for subsequent separation of the liquid vapors from the solution. Such a use would be practical in the separation of water from a sea water solution, for example. When the device is so used it may include further constructional

features to maintain a separation of the vapor from the solution. In FIGURE 1, upright pipes 44 are shown as surrounding the openings 20, 22 and 24, to prevent any liquid solution which is standing within the lower level 5 of chamber 16 from being drawn into the entrainment channel 10. The motive fluid in such an adaptation will produce sufficiently low pressures within the chamber 16 to cause a more rapid evaporation of vapor from the solution. For example, water may be used as a motive fluid, and water vapor will be evaporated from a sea water solution within chamber 16. Upon evaporation, the continued pumping action of the jet pump will draw the water vapor into the entrainment channel 10, where it will be mixed with and ultimately condensed with 10 the motive fluid. The valve 46 may be installed in the inlet 18 to chamber 16 to regulate the flow of liquid solution to the chamber so that the level of liquid will not rise above the top levels of the upright pipes 44. This valve 46 also permits an obstruction to the flow 15 of gases into the chamber 16, and thus may be closed or partially closed to permit a greater evacuation of the chamber 16. With the greater reduction in pressure possible with this device, it is possible to evaporate water vapor from a solution at lower temperatures and at a 20 faster rate than heretofore possible. It has been further found that the motive fluid exhausting from the outlet 25 14 may be recirculated by a suitable pumping means back to the inlet pipe 34. Thus a relatively small quantity of recirculating motive fluid may be used with this device 30 to move much larger volumes of fluid than has been possible with prior art devices.

As an example of a structure which has been constructed in accordance with this invention, a jet pump has been built which used a one square inch diameter inlet 35 pipe 34 and which provided a $\frac{1}{16}$ -inch space between the plates 26 and 28. Further, the length of the outlet slot 14 was 16 inches, thus providing a balance of one square inch inlet with a one square inch outlet. The angle of the walls 30 and 32 from one another in the device 40 constructed was approximately 42° , and the total cross-sectional area of the openings 20, 22 and 24 was several times greater than the one inch area of the inlet pipe. With such a construction it is possible to entrain exceptionally large volumes of fluid per unit volume of motive 45 fluid.

The operation of the FIGURE 1 jet pump can be carefully varied and closely controlled by adjusting the relative dimensions of the channel 10, the inlet and outlet capacities to that channel, and the volume capacities of 50 the openings 20, 22 and 24. It is of particular value that in constructing this pump the operation can be very easily controlled by simply adjusting the spacing between the plates 26 and 28 of the entrainment channel. With such a flat channel construction it is easier to calculate the 55 various effects of adjusting the channel height or its angle of divergence and thus, this jet pump is easily constructed and adapted to fit a variety of engineering requirements. Also, a greater range of motive fluid velocities and pumping capacities can be accomplished with 60 the structure of this device as compared to the prior art constructions, and in any given construction, lower pressures can be produced and greater quantities of fluid can be entrained by the particular expanding shape of this jet pump.

FIGURE 3 represents a sectional view of a second embodiment of the jet pump, and this embodiment illustrates a variation in the entrainment channel for such a device. The device of FIGURE 3 includes an inlet pipe 50 for admitting a motive fluid under pressure into the system, and the motive fluid passes through an entrainment channel 52 to an outlet 54, in a similar manner to the FIGURE 1 system. The FIGURE 3 device also includes an inlet 56 for the admission of fluid which 70 is to be entrained and pumped, and an alternative type 75

of communication 58 is provided between a chamber 60 and the entrainment channel 52.

The entrainment channel 52 of the FIGURE 3 device is formed from spaced plates 62 and 64 at the inlet end of the channel and from the plates 66 and 64 at the outlet end of the channel. The plates 62 and 66 are spaced from the plate 64 in such a way that the vertical spacing $a-a$ between the plates at the inlet end of the channel is greater than the corresponding vertical spacing $b-b$ between the plates at the outlet end of the channel. The reason for adjusting the outlet spacing relative to the inlet spacing is to compensate for the expansion rate of the motive liquid as compared to the rate of entrainment attainable for a fluid as the combined fluids progress toward the outlet end of the channel.

In the device shown in FIGURE 1, the channel 10 is formed from plates 26 and 28 which are essentially parallel to one another. Such a channel configuration receives a motive liquid under pressure at its inlet end and expands the liquid in its progression to the outlet end. As the motive liquid expands across the ever-increasing breadth of the entrainment channel, there is a reduction in pressure in the unit, and thus, a separate fluid may be drawn into and entrained in the motive liquid. It has been found that a point is reached in the entrainment capabilities of the FIGURE 1 device where the entrainment rate may not keep pace with the rate of reduction of pressure within the unit. When this point is reached, the volume of entrained fluid, as combined with the volume of motive liquid, will not be sufficient to fill the expanding volume of the entrainment channel. As a result, there is a danger of atmospheric leakage back into the system (by way of the channel outlet 14), and the reduced pressure conditions within the unit would then be adversely affected. The FIGURE 3 channel 52 has the same top plan configuration as shown in FIGURE 2, but its elevational configuration has been modified by adjusting the spacings of the plates 62, 64 and 66. This modification provides for a smaller volume outlet for the unit, and the combined volumes of motive liquid and entrained fluid can fill this volume without danger of atmospheric leakage back into the system.

The FIGURE 3 illustration shows an exaggerated difference between the spacing at $a-a$ and $b-b$, but it will be appreciated that particular spacings selected will be in accordance with the dimensions and capabilities of the particular device which is constructed. In the FIGURE 3 type of channel the separate plates 62 and 66 are spaced in parallel positions relative to the plate 64, but with the parallel spacing of the plate 62 greater than the plate 66 from the bottom plate 64.

FIGURE 3 also illustrates a modified form of communication opening into the entrainment channel. A single large opening 58 is shown, and no riser walls (corresponding to the pipes 44 of FIGURE 1) are included. The larger opening 58 provides for a greater entrainment area, and such an arrangement is useful where gases are being entrained in motive liquids. Alternatively, riser walls may be provided around the opening 58, as described in the FIGURE 1 embodiment. A top plan view of the opening 58 may be seen by reference to FIGURE 5 where a similar opening is provided in another embodiment of the invention.

The further embodiment which is illustrated in FIGURES 4 and 5 provides for an additional means of compensating for changing entrainment and flow rates within a unit. The entrainment channel 70 of the FIGURE 4 device may be found as in FIGURE 1 or as in the FIGURE 3 embodiment. The channel includes an inlet end 72 for a motive liquid together with an outlet 74 for the combined motive liquid and entrained fluid. Where there is a further possibility of atmospheric leakage back into the system by way of the outlet 74, liquid return pipes 76 are provided to return sufficient liquid into the entrainment channel outlet portion to compensate for in-

sufficient volumes of fluids for occupying the space in the channel. The height and volumes of the return pipes can be selected to provide for a return of liquid only when certain reduced pressure conditions arise in the channel portion between the plates 78 and 80. These conditions would arise when the entrainment rate within the unit is not sufficient to provide for a total volume of fluids which would occupy all of the space between the plates 78 and 80. The compensating liquid volume for use with the apparatus of FIGURE 4 may come from any source, but is shown as being returned from a receiving vessel 82, which receives all fluids exhausted from the outlet 74 of the jet pump.

The FIGURE 5 view of the FIGURE 4 embodiment shows a film of motive liquid 84 expanding past the single large communication opening 86. Alternatively, a plurality of openings or riser walls may be used with the FIGURE 5 apparatus, as was described for the FIGURE 1 structure.

FIGURE 6 illustrates a further way to adjust the outlet area of an entrainment channel in a jet pump of this invention. An end gate 88 is mounted at the outlet end of the entrainment channel 90, and means are provided for adjusting and locking the position of the end gate 88 relative to the channel outlet 92. A simple adjustment means 94 is illustrated in the form of a threaded member which can be unthreaded for moving the end gate up or down and then tightened for locking the end gate in a desired position. The movement of the end gate 88 adjusts the area of the outlet to prevent leakage of air back into the system. The end gate may extend transversely across the entire outlet opening, or alternatively may be positioned in only selected portions of the outlet end of the entrainment channel.

In various pumping uses, such as the pumping or mixing of liquids, it will be appreciated that the jet pumps of this invention may be used in any attitude without affecting their efficiencies. This feature becomes important in certain types of installations and in uses where a pump is traveling in a vehicle which is continually changing its attitude.

Having described several embodiments for the construction of and uses for the jet pump of this invention, it will be appreciated that the invention provides for a device which is efficient in operation and rugged in construction. The jet pump may be easily constructed of sheet material at a lower cost than prior art types of jet pumps, and the dimensions and angles of the device may be adjusted to any engineering requirement for a pumping action of fluids.

It is contemplated, for example, that the jet pump may take the configuration of a complete circle rather than the triangular segment of a circle shown in the figures. In a circular configuration, the inlet pipe 34 of FIGURE 1 would introduce the motive fluid into the center of the circle, and the motive fluid would then expand in all directions on a flat plane outwardly to the periphery of the circle. A similar arrangement could be constructed for the embodiments of the other figures.

Other embodiments and variations will occur to those skilled in the art, and such departures from the description above are intended to be included within the scope of this invention.

What is claimed is:

1. A jet pump apparatus for entraining a fluid with a motive liquid comprising:
a triangular base plate;
a second plate means similar in shape to said base plate and spaced from the base plate to form an entrainment channel between the two plates;
a pair of wall elements between said base plate and said second plate providing two enclosing legs for the channel between the triangular plates;
an inlet means for introducing said motive liquid under pressure into the entrainment channel, said inlet

means being located at the vertex formed by the two legs and plates of the triangular apparatus; an outlet means leading from the entrainment channel at a side of the triangular apparatus opposite from the inlet means and in substantial coplanar alignment with the inlet means, thereby providing a high pressure region of fluid at the inlet end of the assembly and a low pressure region of fluid at the outlet end of the triangular assembly when motive liquid is introduced into the entrainment channel; and communication means through said second plate for receiving the fluid to be circulated and entrained into the motive liquid.

2. The apparatus of claim 1 wherein said second plate means is spaced from said base plate so as to be parallel thereto.

3. The apparatus of claim 1 wherein said second plate means is spaced from said base plate for a greater distance at the inlet end of the apparatus than at the outlet end of the apparatus.

4. The apparatus of claim 1 wherein said second plate means comprises two separate plate elements located at inlet and outlet regions of the apparatus and longitudinally spaced from one another to provide a relatively large exposed communication means and entraining area into said entrainment channel.

5. The apparatus of claim 4 wherein said two separate plate elements are spaced from said base plate for different distances, with a first plate element at the inlet end of the apparatus being spaced farther from said base plate than is a second plate element at the outlet end of said apparatus.

6. The apparatus of claim 1 and including adjustable gate means carried at the outlet end of the apparatus to adjust the area of the outlet opening for the apparatus.

7. The apparatus of claim 1 and including means to add a compensating volume of liquid to an intermediate portion of said entrainment channel for the purpose of satisfying an extreme reduction in pressure in said intermediate portion of the apparatus.

8. The apparatus of claim 7 wherein said means for adding a compensating volume of liquid comprise pipe means communicating with said intermediate portion of the entrainment channel and with a source of liquid which can be drawn through said pipe means and into said channel when pressure becomes reduced within the

channel to a point where there would be atmospheric leakage back into the channel if a compensating volume of liquid were not added.

9. Apparatus for evaporating liquid from a solution comprising:

a chamber for receiving the solution from which the liquid is to be evaporated, and an entrainment channel for removing the vaporized liquid from the chamber;

an inlet means communicating with one end of the entrainment channel for admitting a motive liquid to said channel;

an outlet means leading from an opposite end of said entrainment channel, said outlet means being in substantial axial alignment with said inlet means; a wall common to the bottom of said chamber and the top of said entrainment channel;

at least one opening through said wall whereby the liquid may be vaporized and the vapor drawn from the chamber by the entraining action of the motive liquid; and

an upright pipe means surrounding each last named opening for maintaining a separation of the solution which remains in the chamber from the entrainment channel.

10. The apparatus as defined in claim 9 where said chamber includes a separate inlet means for introducing solution into the chamber and where said separate inlet means includes a valve for resisting the flow of solution to said chamber whereby the liquid level within said chamber may be regulated and pressure within said chamber may be reduced by the entraining action of the apparatus.
